UNITED STATES PATENT OFFICE

63 THOMAS A. PEEBLES, OF MOUNT LEBANON, PENNSYLVANIA, ASSIGNOR TO JOHN M.
HOPWOOD, OF DORMONT, PENNSYLVANIA

WATER CONTROL APPARATUS

43 Application filed July 7, 1928. Serial No. 291,090.

This invention relates to water control apparatus and more particularly to apparatus for controlling the delivery of feed water to boilers and the like.

48 Various forms of feed water regulators have been and are now in use and generally include a throttle valve arrangement which is actuated in response to the water level in the associated boiler for controlling the flow 10 of feed water through the valve to the boiler. As the water level in the boiler rises the control valve is gradually closed and as the water level falls it is gradually opened. For the successful operation of such a valve, it 15 has been found necessary to control, in some way, the pressure drop across the valve. The pressure on the incoming side of the valve must be sufficient to force through the valve the maximum amount of water which the 20 associated boiler will ever need. Obviously, in plants where the boiler ratings are very high at times, this pressure must be considerable. In commercial installations, for obvious practical reasons, it is not possible to 25 fit valves of this type closely, with the result that for low ratings or approximately banked conditions of the boiler, the high differential pressure necessary for maximum load is such that the leakage past the valve is 30 too high for the minimum demand of the boiler such, for example, as occurs when the load or demand for steam is suddenly thrown off from a given boiler.

Various devices and arrangements have 35 been utilized for the purpose of overcoming the above defects and objections, but such devices have been themselves either impractical or unsatisfactory in their mode of operation, especially in times of certain emergencies.

40 An object of this invention is to provide an apparatus of the type set forth of improved construction and arrangement which will be free of the objections to similar apparatus now in use and known to me.

45 A further object is to provide an appa-

ratus of the type set forth which will operate independently of the combustion control system provided in connection with the associated boiler.

50 A further object is to provide a feed water control system of simple construction and arrangement, which will be relatively cheap to manufacture and install and at the same time rugged in construction and reliable in operation.

55 These and other objects which will be apparent to those skilled in this particular art are accomplished by means of the invention illustrated in the accompanying drawing 60 which illustrates diagrammatically a water control apparatus constructed in accordance with one embodiment of this invention.

65 In the particular embodiment of this invention which has been chosen for the purposes of illustration, the feed water supply line is provided with the usual throttle valve for controlling the rate of flow through the line to the associated boiler. Mechanism is provided for opening or closing the valve in accordance with the demand for feed water 70 in the usual manner. Mechanism is also provided for controlling the pressure differential across the throttle valve so that the pressure on the inlet side thereof is varied in accordance with the extent of opening of 75 such valve, or in accordance with the rating at which the associated boiler is being operated.

80 As illustrated, this invention is shown in connection with a boiler drum 5 associated with any desired form or type of boiler furnace 6 and provided with a feed water supply line 7 for supplying the feed water to the boiler. A throttle valve 8 is associated with the supply line for controlling the rate of flow therethrough and mechanism is provided for operating and controlling this valve in accordance with the water level in the boiler.

85 As illustrated, this mechanism includes an inclined metallic tube or tubular member 9

mounted on a supporting bracket 10 and arranged so that its upper end is located above the water level of the boiler and connected to the steam space thereof through piping 11, while the lower end thereof is located below the water level of the boiler and connected to the water space thereof by suitable piping 12. The lower end of the tube 9 is slidably supported on bracket 10, so that it may be movable with relation to the upper end thereof and is fastened to one end of one arm of a bell crank lever 13 by a pin 13'. Bell crank 13 may be pivotally mounted upon any desired support 14. The other arm of crank 13 is pivotally connected by a link 15 to one end of a throttle valve operating lever 16 mounted upon a stationary pivot 17 and operatively connected to the valve stem 18 of the throttle valve.

It is apparent that the tube 9 will contain water to the same level as the level of the water in the associated boiler drum 5 and the upper part of the tube, above the water level, will be filled with steam from the steam space of the drum; also, the water in the lower portion of the tube will be cooler than the steam in the upper portion thereof, with the result that the relative proportions of water and steam in the tube vary as the water level of the boiler drum rises and falls. As the water level falls, a greater proportion of steam enters the tube so that the temperature thereof is raised, causing the tube to expand whereby the length thereof is increased. This expansion results in such a movement of the bell crank lever 13 that the valve operating lever 16 is raised, whereby the throttle valve 8 is opened to increase the flow of feed water to the boiler drum. As the water level in the boiler drum rises the proportion of water in the tube increases, cooling the latter and causing the throttle valve to close, thereby reducing the supply of feed water to the boiler.

Mechanism is provided for controlling the pressure drop across the throttle valve, and this mechanism is so arranged as to increase the pressure of feed water on the inlet side of the valve 8 in accordance with and in proportion to any increase in the extent of valve opening, and to decrease the pressure on the inlet side of the valve in accordance with any decrease in the extent of valve opening. As illustrated, this mechanism includes a valve 19 having associated therewith operating mechanism so arranged that the feed water is delivered to the throttle valve at the desired pressure. This mechanism is illustrated as including a pressure control valve operating regulator 20 of any desired type, but preferably constructed and arranged as disclosed in the Hopwood Patent No. 1,371,243 of March 15, 1921. The pressure responsive element of this regulator may be connected to the feed water supply line at

opposite sides of the throttle valve 8 so as to be responsive to the pressure in the feed water line at opposite sides of the valve. The vertically movable frame 22 of the regulator is connected by a link 23 and a pivoted lever 23' to the valve stem 24 of the pressure controlling valve 19. The counter weights 25 of the regulator are adjusted so as to maintain any desired differential in pressure, or in other words, any predetermined pressure drop across the throttle valve 8 so that, with the mechanism so far described, the pressure controlling valve 19 would be set so as to maintain a practically constant pressure drop across the throttle valve 8. However, mechanism is associated with the regulator 20 so as to modify the effect of the counter weights 25 in accordance with variations in the extent of opening of the throttle valve so as to open the pressure controlling valve 19 to increase the pressure at the throttle valve when the latter is opened, and vice versa.

This mechanism includes a metal bellows 26 connected by a slidable rod 27 to the center of a lever 28, one end of which is connected by a link 29 to the throttle valve operating lever 16, and the other end of which is connected by a link 30 to a valve plug 31 mounted in a housing 32 having one port connected to a pressure line 33 for delivering fluid pressure from any desired source (not shown), a second or exhaust port connected with an exhaust line 34 and a third port, adapted to be connected by the plug 31 to either of the first named ports and associated with a line 35 communicating with a line 36 leading to the interior of the metal bellows 26 and with a second branch line 37 leading to the interior of a second metal bellows 38, the upper end of which is connected by a link 39 with the counter weight supporting lever 40 of the regulator 20, through a small lever 41 pivoted at 42. The valve plug 31 is so formed that the slightest movement thereof will connect the line 35 and branch lines 36 and 37 with either the high pressure line 33 or the exhaust line 34.

Assuming that the demand for steam is increased, resulting in increased steam generation and the lowering of the water level in the boiler drum 5, the water level will also be lowered in the tube element 9, increasing the temperature thereof so as to open the throttle valve 8 and increase the flow of feed water to the boiler. This operation raises the throttle valve operating lever 16 and this, in turn, causes the lever 28 to be rotated in a counter clockwise direction as shown in the drawing, thus lowering the valve plug 31 and connecting the line 35 with the supply line 33 admitting pressure to the bellows 26, raising the stem 27 and returning the valve plug 31 to neutral position. The connection of the pressure line 33 with the line 35 has also increased the pressure in the line 37 and the

bellows 38 adding to the effect of the counter weights 25 and lowering the crosshead 22 of the regulator so as to open the pressure controlling valve 19, delivering the feed water to the throttle valve 8 at a higher pressure and increasing the pressure drop thereacross. As the demand for steam decreases, and the water level in the boiler drum 5 raises, the reverse operation will occur and the closing of the throttle valve 8 will raise the valve plug 31, connecting the interior of the bellows 26 and the bellows 38 with the exhaust line 34, thus lowering the pressure therein which, in turn, causes the sliding rod 27 on the bellows 26 to be lowered, returning the valve plug 31 to normal and at the same time reducing the effect of the bellows 38 on the regulator 20, resulting in a closing movement of the pressure control valve 19.

It will, of course, be readily understood that the feed water supply line 7 is associated with a pumping mechanism (not shown) which supplies the water to the pressure controlling valve 19 at a pressure sufficiently above the boiler pressure to insure the maintenance of the required maximum differential across the throttle valve 8 when the latter is fully open.

It will be apparent that the present invention provides a system for regulating feed water which operates independently of any associated combustion control system and which controls the pressure differential across the feed water valve in accordance with the flow of water to the boiler, or in other words, in accordance with the extent of opening of the valve. As the load on the plant is increased and there is a demand for additional feed water, the throttle valve gradually opens and this, in turn, effects a corresponding increase in the differential pressure, the latter reaching a maximum when the valve is wide open. An important feature of this invention is the fact that the position of the throttle valve determines the pressure drop across it.

Thus, if it were not for the bellows 38, and 26, and their associated mechanisms, the regulator 20 would operate upon the control valve 19 to maintain the pressure drop or differential across the throttle valve 8 at a constant value. But, by reason of the upper bellows 26 and the valve plug 31, each increment of rise of the valve stem 18 and consequent opening of throttle valve 8, is represented by a given increment of pressure, momentarily permitted by the plug valve 31 to enter from the pressure line 33 into the line 37 and bellows 26 and 38. This pressure increment, by reason of its simultaneous action upon the bellows 26, causes the lever 27, and thus, the point of pivot of the lever 28, to rise by a like, or if desirable, by a given increment.

The action of bellows 26, as above described, tends to allow only the pressure in-

crement, representative of a given rise of the valve stem 18, to pass into the line 37, and when that increment has been sent out, to immediately raise the pivot point of lever 28 and the associated plug valve 31 sufficiently to close off the pressure flow from line 33 to line 37.

The action of bellows 38 tends to lessen the effectiveness of the weight 25 and to change the pressure differential maintained by the device 20 in steps represented by pressure increments sent into the line 37 and produced primarily by the "stepping up" of the valve stem 18 and consequent opening of the valve 8. Thus, it will be noted that the operation of the demand responsive valve 8 results in a raising or lowering of the pressure differential ratio maintained by the regulator 20.

Although it appears desirable for the use shown in the embodiment of my invention chosen for the purposes of illustration to increase the pressure differential ratio as the valve 8 opens, and in like manner, to decrease the ratio as the valve closes, yet, it must be understood that I do not wish to so limit the scope of my invention. For, the bellows 38 may be levered in a manner to aid the weight 25 when the valve 8 is being opened, and to reduce the effectiveness of the weight when the valve is being closed, instead of the opposite arrangement as above described.

Although I have described a particular arrangement of this invention in more or less detail, it will be apparent that various changes, additions, substitutions, and omissions can be made therein without departing from the spirit of this invention or the scope of the appended claims.

What I claim as new and desire to secure by Letters Patent is:

1. In combination with a boiler having a feed water line, a feed water control valve in said line, means for operating said valve in response to demand for feed water by said boiler, pressure control means for varying the water pressure in said line on the inlet side of said valve, and an additional mechanism responsive in operation to the drop in pressure across said valve and the position of said valve controlling said pressure control means for increasing the pressure differential across said valve as said valve opens and for decreasing such pressure differential as the valve closes.

2. The combination with a boiler having a feed water supply line connected thereto, a throttle valve in said line, means responsive to variations in the water level in the boiler for operating the throttle valve, and a valve in said line adapted to vary the water pressure on the inlet side of the throttle valve, of pressure actuated mechanism operating independently of the pressure in the feed water supply line and the boiler and

controlled by and in accordance with the position of the throttle valve for actuating said second mentioned valve so as to increase the pressure at the inlet of the throttle valve as the throttle valve opens and to decrease the inlet pressure as the throttle valve closes, said pressure actuated mechanism including means responsive to the pressure drop across the throttle valve for so actuating said second mentioned valve as to maintain the differential resulting across the throttle valve, for each position thereof, substantially constant.

In testimony whereof, I have hereunto subscribed my name this 28th day of June, 1928.
